APPARATUS FOR PREPARING BLOOD FILMS
FOR THE MAKING OF DIFFERENTIAL
COUNTS

David J. B. Lubin, San Francisco, Calif.

Application April 24, 1935, Serial No. 17,989

4 Claims. (Cl. 88—40)

This invention relates to an apparatus for preparing blood films on glass slides or cover-slips for the purpose of studying the individual blood cells, and more particularly, for making differential counts.

There are two distinct methods of preparing blood films on glass slides or cover-slips for the purpose of studying individual blood cells, and more particularly, for making differential counts.

10 The first method is the least difficult but is the most inaccurate. In this method a drop of blood is placed on a slide, usually at one end thereof, and it is then spread out into a thin film by pushing it along with the end or edge of another slide, or with a cover-slip, or with a piece of celluloid. With this method the blood is spread out evenly but because some of the white blood corpuscles are heavier than others, they are pushed out to the edges of the film, 20 thus making a very untrustworthy and poor distribution, which, of course, makes accurate differential counting impossible.

The second method is more difficult but it gives the most accurate distribution of white 25 blood cells so that differential counting may be carried on with a remarkable degree of accuracy. This method consists in holding one cover-slip in one hand, placing a small drop of blood in the center of it, and then dropping or laying 30 another cover-slip over the drop of blood. When the blood has been spread out into a film by the weight of the top cover-slip, the top cover-slip is pulled off in a plane parallel to the bottom slip and a blood film is formed on both cover-slips.

There are several difficulties encountered when making blood films by the second method or what is known as the "two cover-slip method."

First.—Difficulty in handling the thin cover-slips. They break easily and are bent or buckled if too much pressure is exerted in holding them;

Second.—Difficulty in pulling the top slide off the bottom slide while maintaining it in the same plane as the bottom slide is encountered;

45 Third.—Difficulty in keeping a constant degree of non-extraneous pressure of the top cover-slip on the bottom slip; and

Fourth.—Difficulty in making all films as nearly alike as possible due to differences in 50 pressure when pulling the cover-slips apart by hand.

The object of the present invention is to generally improve and simplify the operation and making of blood films by the two-cover-slip 55 method, and in particular, to provide an appara-

tus whereby uniform pressure between the cover-slips is insured; breakage and bending of the cover-slips is prevented; parallelism between the contacting surfaces of the cover-slips is maintained; and, further, to provide an apparatus in which the cover-slips can be readily inserted and secured and quickly released and removed when the blood films have been made.

A form of apparatus suitable for the preparation of films of blood is shown by way of illustration in the accompanying drawing, in which—

Fig. 1 is a perspective view of the apparatus; showing one position of the cover slips;

Fig. 2 is a similar perspective view of the apparatus showing a second position of the cover slips;

Fig. 3 is an enlarged vertical longitudinal central section of Fig. 1; and

Fig. 4 is a cross section on line IV—IV of Fig. 3.

Referring to the drawing in detail, A indicates 20 a rectangular-shaped base member constructed of wood, bakelite, or any other suitable material. Formed in the upper surface of the base and extending substantially from end to end thereof is a dovetail slot 2 and movable longitudinally 25 thereof is a sliding block B, having a tongue 3 extending into the slot to be guided thereby. Stop members 4 and 5 are disposed at opposite ends of the slot and prevent removal of the sliding block and also limit longitudinal movement.

Carried by the sliding block is a pair of spring clamping arms 6. These arms are pivoted to the block and are secured against removal by a plate 7, screwed, riveted, or otherwise fastened to the block. The center portions of the arms are bent inwardly or toward each other, as shown at 8, and are then spread apart and bent downwardly, as indicated at 9, to straddle the opposite sides of the block. The spring arms are employed for the purpose of receiving and securing a cover-slip such as indicated at 10, this slip being placed in position between the spring arms by merely inserting one of the fingers between the inwardly bent or contracted portions 8 of the arms to 40 spread them apart, and then inserting the cover slip between the outer downwardly bent portions 9 which will grip and clamp the opposite sides of the slip the moment the finger spreading the arms apart is removed. The cover-slip, when placed between the arms, will rest upon the flat upper surface of the sliding block and will be held by it. After insertion of the slip the sliding block is moved to the position shown in Fig. 1 and the blood sample is placed thereon and on top of this 50 55

is placed a second cover-slip, such as shown at 11. The first cover-slip is placed between the spring arms with its sides parallel to the sides of the sliding block, while the second cover-slip, when placed on top thereof, is positioned with its sides on an approximate angle of 45° with relation to the sides of the sliding block and it is held in this position by a pair of pins 12—12 secured in the base on opposite sides of the sliding block. These pins are, in the present instance, connected at their upper ends by a cross member 14. This member serves the function of maintaining the spacing between the pins and to a certain degree prevents bending of the same.

15 With the cover-slips positioned, as shown in Fig. 1, and with the blood sample placed between the same, the only operation necessary to obtain the blood film is that of sliding the block from the position shown in Fig. 1 to that shown in Fig. 2. 20 During this movement the upper cover-slip 11 will be held stationary by the pins 12—12, while the lower cover-slip 10 will move in unison with the block from in under the same. During this movement a film is formed on the adjacent faces 25 of the respective cover-slips and two films will be obtained. To prevent smearing of the film formed on the lower surface of the cover-slip 11, a pair of raised surfaces 15 are provided. These may be formed by driving elongated staples into 30 the sliding block, or in any other desired manner. Suffice it to say, that as the sliding block is moved from the position shown in Fig. 1 to that shown in Fig. 2, the stationary cover-slip 11 is transferred from its position of rest on top of the 35 cover-slip 10 to a position of rest on top of the raised members 15. It is for this reason that smudging of the film is prevented.

After the films are formed each cover-slip may be removed and dried in the usual manner. The 40 results obtained by the use of an apparatus of this character are exceedingly uniform as absolute parallelism between the contacting faces of the cover-slips is maintained at all times. Uniform pressure is also insured and bending or 45 breaking of the cover-slips is prevented. Furthermore, the apparatus makes available a means of making blood films by means of the two cover-slip method, both to amateurs and experts, and the result obtained is more perfect 50 than can be obtained by the most expert hand operation; the final result being the preparation and production of a blood film whereby differential counting may be carried on with a remarkable degree of accuracy.

55 While certain features of the present invention are more or less specifically described, I wish it understood that various changes may be resorted to within the scope of the appended claims. Similarly, that the materials and finish of the several 60 parts employed may be such as the manufacturer may decide, or varying conditions or uses may demand.

Having thus described my invention, what I claim and desire to secure by Letters Patent is:—

65 1. In an apparatus for preparing a film of blood

between a pair of cover-slips, a base member, a block mounted on the base and longitudinally movable thereon, means on the block for receiving and securing one of the cover-slips, said second cover-slip adapted to be placed on top thereof, means on the base engageable with the second cover-slip to hold it against movement when the block and the first cover-slip are moved longitudinally on the base, and means on the block for receiving and supporting the second cover-slip 10 when the first cover-slip is moved from in under the same. 5

2. In an apparatus for preparing a film of blood between a pair of cover-slips, a base member, a block mounted on the base and longitudinally movable thereon, means on the block for receiving and securing one of the cover-slips, said second cover-slip adapted to be placed on top thereof, means on the base engageable with the second cover-slip to hold it against movement 15 when the block and the first cover-slip are moved longitudinally on the base, and a pair of spaced raised supporting members on the block to receive the second cover-slip when the first-named cover-slip is moved from in under the same. 20 25

3. In an apparatus for preparing a film of blood between a pair of cover-slips, a base member, said base having a groove formed therein and extending longitudinally of the base, a block mounted on the base and having a tongue extending into the groove, said block being movable longitudinally of the base and being guided by the tongue and groove, a pair of spring clamping arms on the block to receive and secure one of the cover-slips, said second cover-slip adapted to be placed 30 on top thereof, a pair of pins secured to the base, one on each side of the block and engageable with the second cover-slip to secure it against movement when longitudinal movement is imparted to the block and the first-named cover-slip secured 35 thereto, and a pair of spaced raised supporting members on the block to receive the second cover-slip when the first-named cover-slip is moved from in under the same. 40

4. In an apparatus for preparing a film of 45 blood between a pair of cover-slips, a longitudinally movable member to receive and secure one of the cover-slips, said second cover-slip adapted to be placed on top thereof in a position where the adjacent surfaces of the cover-slips will be 50 parallel and where blood placed on the first cover-slip will be spread out into a film by the weight of the second cover-slip only, means for holding the second cover-slip against movement whereby when movement is imparted to the movable 55 member the first cover-slip will be pulled out from in under the second cover-slip in a plane parallel to the surface of the second cover-slip, and equal films will be formed on the adjacent surfaces of the cover-slips, and means for receiving and supporting the second cover-slip when the first-named cover-slip is pulled out, said means preventing smearing of the film formed on the second cover-slip. 60
